UNITED STATES PATENT OFFICE.

AXEL JOHNSON, OF OAKLAND, CALIFORNIA, ASSIGNOR TO AMERICAN CAN COMPANY, OF SAN FRANCISCO, CALIFORNIA, A CORPORATION OF NEW JERSEY.

CAN-BODY-MAKING MACHINE.

1,101,446.

Specification of Letters Patent. Patented June 23, 1914.

Application filed August 1, 1913. Serial No. 782,507.

To all whom it may concern:

Be it known that I, AXEL JOHNSON, a citizen of the United States, residing at Oakland, in the county of Alameda and State of California, have invented certain new and useful Improvements in Can-Body-Making Machines, of which the following is a specification.

The hereinafter described invention relates to that class of machines used for the manufacture of what is known as lap joint can bodies, it relating more particularly to the construction of the clamping jaws and the associated mandrels; the means for actuating the clamping jaws to close and open the same during the movement or travel of the mandrels, and in the stationary gage plate for limiting the folding movement of the can body blank as formed around the mandrel, and for positioning the lap edge of the can body blank to lie over the held edge of the said blank as they are carried beyond the feed mechanism for the can body blanks.

To comprehend the invention, reference should be had to the accompanying sheets of drawings, wherein,

Figure 1 is a broken plan view of the apparatus, illustrating a portion of the frame and the endless carrier, a series of the clamping jaws with associated mandrels, the feed mechanism for the can body blanks, and the shipper devices for receiving the can bodies from the traveling mandrels. Fig. 2 is an enlarged detail view disclosing a series of horns or mandrels, illustrating the manner of truing the can body blank after having been rolled around the horn or mandrel. Fig. 3 is an enlarged sectional view taken on line X X Fig. 1 of the drawing, disclosing the feed mechanism for the can body blanks, a blank rolled around the horn or mandrel, the gage plate for the can body blank, and the position of the clamping jaws just prior to being closed. Fig. 4 is a detail part sectional end view in elevation, illustrating the shipper device and its application for removing a can body from its horn or mandrel. Fig. 5 is an edge view of the can body shipper.

In the drawings, the numeral 1 is used to designate any suitable form of a supporting structure or frame, to which the horizontally disposed spaced guide rails 2—2' are

secured. Between these guide rails works 55 the endless conveyer, which conveyer is composed of a series of links 3 hinged together by means of the vertical pins 3', the said pins having secured to the projecting ends thereof the rolls 4—4', which rolls work 60 within the grooves 5 of the guide rails 2—2', Fig. 3 of the drawings. The said endless conveyer is driven by means of the horizontally disposed drive wheels 5', arranged at each end of the machine between the curved 65 end portions of the guide rails 2—2', only one of such drive wheels being illustrated in the present case, Figs. 1 and 2 of the drawings. The said drive wheels 5' have motion imparted thereto by the usual actuating 70 means, which requires no description for an understanding of the present invention.

Each link 3 of the endless conveyer, is provided with an outwardly extended bracket 6, to which bracket the clamping 75 jaws 7—7' are hinged by means of the pin 6', to the tail extensions 8—8' of the respective clamping jaws there are hinged the cranks 9—9', positioned respectively by means of the tension spring 11, and the adjusting screw 10, Fig. 3 of the drawings. The section 7² thereof may have a slight inward movement after the associated mandrel or horn of the clamping jaws has been carried beyond the can body blank feed 85 mechanism, in order that the lap edge of the can body blank may be depressed after the rolled can body blank has moved from beneath the gage plate, so as to force and hold the lap edge of the blank firmly down onto 90 the under edge of the rolled can body blank 18.

Each of the brackets 6 is formed with an upwardly projecting arm 13', to which is secured the horizontally disposed horn or 95 mandrel 14, which is situated within the cylinder formed by the clamping jaws 7—7', and held so as to leave a clearance space between the parts, when the said clamping jaws are in an open position, as shown, Fig. 100 3 of the drawings.

The rolls 15, carried by the lower extending arms of the crank levers 9—9', ride on the vertical faces of the cam rail 15', which rolls work on the enlarged portion 16 of the 105 cam rail as the clamping jaws are carried around by the endless conveyer, and act as the means for forcing apart the crank levers

9—9' in order to close the clamping jaws 7—7' onto the can body blank 13 rolled onto the horn or mandrel 14. The cam rail 15' commences to gradually enlarge at a point 5 slightly in advance of the feed mechanism for the can body blanks, and the enlarged portion 16 thereof terminates at a point slightly in advance of the stripper 16' for the can bodies, Fig. 1 of the drawings, so 10 that the clamping jaws commence to close as the can body blank 13 is loosely rolled around the horn or mandrel associated therewith, and remain closed against the rolled can body blank until after the same has been 15 carried beyond the soldering mechanism, not shown, the said rolls leaving the enlarged portion of the cam rail as the clamping jaws approach the stripping device. As the rolls 15 begin to bear against the faces of such 20 reduced portion of the cam rail, the same move toward each other and the weight thereof throws the crank levers 9—9' inwardly to open the clamping jaws.

The can body blanks 13 are delivered to 25 the feed rollers 17—17' by means of the endless chain blank carrier 18, which carrier works over the sprocket wheels within the frame 18', the overhanging forward portion thereof having mounted therein the said 30 feed rolls 17—17'. These rolls and the sprocket wheels for the endless body blank carrier are suitably driven, as shown in Fig. 3 of the drawings.

As the can body blanks pass between the 35 feed rolls 17 and 17', the same bear against the under face of curved deflector plate 17², which deflects and causes the rolling of the same around the horn or mandrel 14 positioned beneath the feed rolls. The deflector 40 plate 17² is arranged in front of the rolls 17 and 17', projecting outwardly from the supporting plate 17³ adjustably mounted within the bracket arms 18², the said supporting plate being raised and lowered by 45 means of the adjusting screws 18³.

Immediately below the feed roll 17', there is located the gage plate 19', which plate is held within the overhanging portion of the frame 18' and the same is so positioned as to 50 lie directly upon the horn or mandrel 14, as the same passes beneath the feed rolls. As the horn or mandrel 14 travels beneath the said rolls, the can body blank is loosely rolled around the same until the forward 55 edge thereof engages the rear shouldered portion 20 of the gage plate 19', by which time the outer end or edge portion thereof will overlap the knife edge surface of the end gage plate 19', when the clamping jaws 60 will have partly closed down onto the loosely rolled can body blank. However, as the horn or mandrel has moved longitudinally during the rolling of the can body blank around the same, the said horn or mandrel 65 and its associated clamping jaws will be

slightly in advance or beyond the loosely rolled can body blank, so that the rolled blank projects somewhat outside of the partly closed clamping jaws, Fig. 2 of the drawings. To true the rolled can body blank 70 within the clamping jaws, prior to the same closing firmly onto the loosely rolled can body blank, each upwardly projecting arm 13' is provided with a forwardly projecting extension 20', which extension, when the horns or mandrels are in axial alinement, bears against the rear end of the horn or mandrel immediately preceding the mandrel arm to which it is attached. As one horn or mandrel is having a can body blank rolled 75 thereon, the succeeding horn or mandrel is being carried around the forward drive wheel 3', but by the time the can body blank has been rolled around the horn or mandrel, the succeeding horn or mandrel will have 80 completed its turn and be in axial alinement with the preceding horn or mandrel and as brought into such alinement its projecting extension 20' is forced against the rear end of such horn or mandrel so as to gradually 85 force the projecting end of the rolled can body blank inwardly to true the end of the said blank with its horn or mandrel. This will be readily understood by reference to Fig. 2 of the drawings, wherein the relative 90 position of a series of horns or mandrels, with their associated clamping jaws is illustrated.

By the time the rolled can body blank has been trued to its horn or mandrel, the said 95 horn or mandrel will have been carried beyond the feed mechanism for the can body blanks and the associated clamping jaws firmly closed down onto the rolled blank, due to the rolls 15 being carried onto the 100 enlarged portion of 16 of the cam rail 15', which jaws as closed around the horn or mandrel 14 force the lap edge of the rolled can body blank down onto the under edge thereof, the said lap edge having been properly positioned by means of the gage plate 105 19'. The clamped can body blank is then 110 conveyed to and past the usual solder applying mechanism, not shown, for the soldering of the lap seam of the rolled can body blank 115 to form the seamed can body, the held can body being then conveyed by the movement of the endless carrier toward the stripper 16' for the removal of the can body from its horn or mandrel. As the horn or mandrel with 120 its held can body approaches the stripper 16', which is situated at the forward curved end portion of the apparatus, the rolls 15 of the crank levers controlling the movement of the clamping jaws enter onto the 125 reduced portion or are carried off of the enlarged portion of the cam rail 15', so as to gradually swing the crank levers 9—9' inwardly to open the clamping jaws and release the soldered can body, so that by the 130

time the held can body reaches the stripper 16', the clamping jaws 7-7' will stand full open, Fig. 4 of the drawings, and the soldered can body will be free to be slipped from the horn or mandrel 14. As the said horn or mandrel is carried past the stripper 16', the inwardly flanged ends 21 thereof engage the forward end of the soldered can body 22, and hold the same against movement, while the endless carrier continues its travel. The flanged ends 21 of the stripper 16' fit within the longitudinal grooves 22' of the horn or mandrel, so that the said horn or mandrel is free to slip from within the can body thereon. In order that the stripper 16' may conform to the direction of movement of the curved path of the horn or mandrel as conveyed around the forward end of the apparatus, the said stripper is attached to a vertical rod 23 rotatably held in the supporting frame 23', which frame is fulcrumed to the bracket 24 upwardly and outwardly projecting from the forward end of the apparatus. The frame 23' is thus permitted to swing in accordance with the changed position of the horn or mandrel as carried around the curved end of the machine, its swinging movement being limited by means of the arm 25, the slotted portion 14' of which fits over the pin 25' projecting from the bracket 24. The stripper 16' may be located at any desired point within the line of travel of the horns or mandrels after they have been conveyed beyond the location of the soldering mechanism, but preference is given to the placing of the same at the forward curved end portion of the apparatus, so as to give the solder applied to the lap joint ample time to cool prior to the can body being removed from its horn or mandrel.

Having thus described the apparatus, what is claimed as new and desired to be protected by Letters Patent is—

1. In an apparatus for the described purpose, the combination with a supporting frame or structure, of spaced guide rails held thereon, an endless carrier working on said guide rails, a series of forming horns or mandrels carried by said endless carrier, clamping jaws associated with each horn or mandrel and supported by the said carrier, devices for actuating the said jaws to close and open the same during the travel of the horns or mandrels, mechanism for feeding and rolling can body blanks directly onto the forming horns, a gage plate adjacent the feed mechanism, and provided with a shoulder on its inner face for limiting the movement of the can body blanks onto the horns or mandrels and placing the lap edge thereof, and means for removing the formed can body from the traveling horns or mandrels.

2. In an apparatus for the described purpose, the combination with a horizontally

disposed endless flexible carrier having laterally extended arms, of a series of forming horns or mandrels carried thereby, a series of clamping jaws associated with the horns or mandrels, said clamping jaws being supported and propelled by the endless carrier, means for feeding and rolling can body blanks directly onto the forming horns, a gage plate projecting over the path of the horns adjacent the said feeding means for the can body blanks for limiting the curling movement thereof around the horns, controlling means for closing and opening the said clamping jaws, and a cam rail on which said controlling means works during the travel of the endless carrier.

3. In an apparatus for the described purpose, the combination with an endless carrier of a series of brackets extended therefrom, a horn or mandrel carried by each of the brackets, clamping jaws hinged to each bracket for clamping a loosely formed can body blank onto its horn or mandrel, devices for actuating said clamping jaws during the movement of the endless carrier, mechanism for delivering can body blanks to the traveling horns or mandrels and rolling the same directly thereon, and means carried by the horns or mandrels for truing the rolled can body blanks as the horns or mandrels move into axial alinement in their approach toward the feeding mechanism for the can body blanks.

4. In an apparatus for the described purpose, the combination with an endless carrier of a series of horns or mandrels carried thereby, a series of clamping jaws associated with the horns or mandrels, said jaws being held to the endless carrier, devices for actuating said clamping jaws, mechanism for delivering can body blanks to the horns or mandrels and rolling the same directly thereon, means carried by the horns or mandrels for truing the loosely rolled can bodies as the horns or mandrels move into axial alinement in their approach toward the feeding mechanism, and a device arranged within the path of the traveling horns or mandrels for stripping therefrom the formed can bodies.

5. In an apparatus for the described purpose, the combination with a horizontally disposed endless flexible carrier having laterally extended arms of a series of horns or mandrels carried thereby, clamping jaws associated with each horn or mandrel, devices for actuating said jaws, mechanism for feeding can body blanks to the horns or mandrels and rolling the same directly thereon, and a gage plate adjacent the feeding mechanism for limiting the movement of the can body blank onto the horns or mandrels and positioning the lap seam thereof.

6. The combination with an endless car-

rier having a series of horns and a series of clamping jaws, of rolls for feeding and rolling the can body blanks directly onto the horns, and a gage plate projecting over the path of the horns adjacent to said feed rolls and provided with a shoulder on the face thereof adjacent to the horns for limiting the feeding and rolling or curling movement of the can body blank around the 10 horns, substantially as specified.

7. The combination with an endless carrier having a series of horns and a series of clamping jaws, of rolls for feeding and rolling the can body blanks directly onto the 15 horns, and a gage plate projecting over the path of the horns adjacent to said feed rolls provided with a shoulder on the face thereof adjacent to the horns for limiting the feeding and rolling or curling movement of the can body blank around the horns, said 20 gage plate having a projecting thin blade for placing and supporting the lap edge of the body blank in respect to the inner edge thereof, substantially as specified.

8. The combination with an endless carrier having a series of horns and a series of clamping jaws, of rolls for feeding and rolling the can body blanks directly onto the horns, and a gage plate projecting over 30 the path of the horns adjacent to said feed rolls provided with a shoulder on the face thereof adjacent to the horns for limiting the feeding and rolling or curling movement of the can body blank around the 35 horns, and means for continuously moving said carrier to the horns thereof, substantially as specified.

9. The combination with an endless carrier having a series of horns and a series of 40 clamping jaws, of rolls for feeding and rolling the can body blanks around the horns, and a gage plate projecting over the path of the horns adjacent to said feed rolls provided with a shoulder on the face thereof adjacent to the horns for limiting the feeding and rolling or curling movement of the can body blank around the horns, means 45 for continuously moving said carrier to the horns thereof and means for positioning 50 the can bodies longitudinally on the horns

before said clamping jaws tightly close around the horns, substantially as specified.

10. The combination with an endless carrier having a series of horns and a series of clamping jaws, of rolls for feeding and 55 rolling the can body blanks around the horns, and a gage plate projecting over the path of the horns adjacent to said feed rolls provided with a shoulder on the face thereof adjacent to the horns for limiting the feeding and rolling or curling movement of the can body blank around the horns, one 60 of said clamping jaws having a yielding section, substantially as specified.

11. In a side seam can body forming 65 machine, the combination with a continuously driven endless carrier, of a plurality of forming horns carried thereby, means for feeding and rolling can body blanks directly onto the forming horns and gaging the lap edge of the rolled blanks, and clamping jaws associated with each horn or mandrel for clamping the rolled can body blanks thereon and maintaining the edges 70 overlapping.

12. In a side seam can body forming machine, the combination with a continuously driven endless carrier, of a plurality of forming horns carried thereby, means for feeding and rolling can blanks directly onto 80 the traveling horns and gaging the lap edge of the rolled body blanks, clamping jaws associated with each of the horns for clamping the rolled can body blanks thereon and maintaining the edges overlapping, devices 85 controlling the opening and closing movements of the clamping jaws during the movement of the endless carrier, and means carried by each clamping horn for positioning the rolled can bodies on the preceding 90 horn before said clamping jaws tightly close around the horns.

In testimony whereof I have signed my name to this specification in the presence of two subscribing witnesses.

AXEL JOHNSON.
